Attorney

UNITED STATES PATENT OFFICE.

ALFRED JAESCHKE, OF LOS ANGELES, CALIFORNIA.

CAN-SPOUT-SEAL CUTTER.

Application filed September 25, 1926. Serial No. 137,707.

My invention relates to can spout seal cutters and has for its object to provide an article of manufacture which shall be simple in construction and inexpensive to manufacture and 5 adapted to the purpose intended.

With the above and other objects in view, my invention consists in the combination and arrangement of parts hereinafter described and claimed, it being understood that, within 10 the limits of what is claimed, changes may be made in the precise embodiment shown without departing from the spirit of the invention.

In the drawings

15 Figure 1 is an elevation partly in section of my invention in use in a can spout;

Figure 2 is a plan view of my invention;

Figure 3 is a section along the line 3—3 of Figure 2;

20 Figure 4 is a plan view of a can spout after having the seal cut by my device.

In the merchandising of certain liquids, it is expedient to provide sealed cans or containers for the purpose in order that no 25 vapors may escape and also to reduce the fire danger. In a form of construction of such cans well known to those skilled in the art, a can 10 is provided with a spout 11 and a cap 12 threaded to said collet. Positioned inside 30 the said spout is the seal or diaphragm 13 which must be cut or perforated in order to remove the contents of the can.

In the embodiment shown, my invention consists of a tube A adapted to rotatably engage the inside of the spout 11, and having a 35 plane end as at 14, and a longitudinal slot as at 15, whereby the said tube may be frictionally inserted in said spout; a triangular cutter 16 is formed integrally the plane end 40 of the said tube and inset radially form the periphery of the tube as shown at 17.

In the use of my invention the tube A is frictionally inserted in the spout 11, the said spout then acting as a guide for the tube; and the plane end of the tube resting on the metal 45 to be cut, as at 19, the tube is caused to be rotated by grasping with the hand, whereby a circular disc as at 20, will be cut from the seal and the can thus opened for the removal of its contents, as at 18.

50 I claim:

1. In a device for cutting a metal can spout seal, a tube having one end adapted to rest upon the seal, said tube also having a longitudinal slot from end to end whereby 55 said tube is adapted to have its entire perimeter shortened so as to frictionally and rotatably engage the interior of the spout, and a portion of the wall of the tube being extended to form a dependent cutting element, said 60 element being projected from the wall of the tube radially inwardly thereof and adapted to pierce said seal with a circular path when said tube is rotated whereby to leave an annular portion of the seal for the tube to rest 65 upon while being rotated.

2. In a device of the kind described, a tube substantially of greater length than the depth of the spout, said tube having a longitudinal slot from end to end so as to be adapted to 70 have its entire perimeter shortened for frictional and rotational engagement with the interior of the spout, and said tube also having a dependent cutting element inset radially 75 inwardly from the perimeter of the tube and adapted to pierce the seal with a circular path when the tube is rotated so as to leave an annular portion of the seal for the tube to rest upon while being rotated.

In testimony whereof I affix my signature.

ALFRED JAESCHKE.
